UNITED STATES PATENT OFFICE.

WILLIAM EDWARD LIST, OF ADDISCOMBE, ENGLAND.

APPLIANCE FOR CLEANING TOOTHED ARTICLES.

1,155,747.

Specification of Letters Patent.

Patented Oct. 5, 1915.

Application filed November 21, 1914. Serial No. 873,289.

To all whom it may concern:

Be it known that I, WILLIAM EDWARD LIST, a subject of the King of Great Britain, residing at 18 Bingham road, Addiscombe, Surrey, England, have invented a new and useful Appliance for Cleaning Toothed Articles, of which the following is a specification.

My invention relates to a simple and efficient appliance for cleaning pronged or toothed articles, such as toilet-combs, table-forks, and the like.

According to the invention my improved appliance comprises a series of threads, fibers, wires or the like, in combination with one or more brushes, the arrangement being such that the comb or the like to be cleaned is passed through the fibers, threads, or the like, and through the bristles of the brush, and passed along the same, the brush or brushes removing any matter which is drawn out from the spaces between the teeth or prongs of the comb, or other articles, by the passage of the latter along the said fibers.

In practice, I advantageously make use of horse-hair as the threads or fibers, and of woven horse-hair fabric as the brush or brushes, and in a suitable form of appliance particularly adapted for the cleaning of toilet-combs. The clearing hairs and the brush or brushes are made from a strip of woven horse-hair fabric, the warp threads of which have been removed to form a series of parallel horse-hairs, the ends of the strip being turned over so as to serve as the brush, and the warp threads being retained at the turned-over portion. An additional layer or layers of fabric may be fitted at either end so as to make a thicker or more effective brush.

In applying the invention to an appliance for cleaning table-forks, the fibers or the like, which are preferably of horse-hair, are advantageously arranged in bundles. The said bundles may be stretched parallel to one another in holding devices of any convenient shape. At either or both ends a brush, which may be made from horse-hair woven fabric or from bristles or fiber, may be suitably secured to the holding devices, and the length of the bristles of the brush may be selected so that the combined effect of the brush and clearing bristles is most efficient for the particular articles for which the appliance is designed. In some cases

I may combine with the horse-hair or the equivalent, means for polishing an article such as a fork; for example, the device may be furnished with a material such as wool or chamois leather, and with a polishing powder or substance such that the fork is polished as it is passed through the appliance.

To enable the invention to be fully understood I will describe it by reference to the accompanying drawings, in which:

Figure 1 is a front view of an appliance for cleaning toilet-combs, made according to the invention. Fig. 2 is an edge view thereof, and Fig. 3 is a section on the line 3—3, Fig. 1, but showing an exaggerated thickness of the parts. Fig. 4 is a front view of a somewhat modified form of the appliance. Fig. 5 is an edge view thereof, and Fig. 6 is a section on the line 6—6, Fig. 4, also showing an exaggerated thickness of the parts.

Referring first to the appliance shown in Figs. 1 to 3, *a* represents a series of parallel fibers which are in the construction illustrated, of horse-hair, provided by the removal of the warp threads from a strip *b* of woven-horse-hair fabric. The strip *b* is folded longitudinally as shown in Fig. 3, so as to provide a double layer or thickness of the parallel horse-hairs *a*, and the two ends of the double strip so formed are then turned-over and passed through the two loops or handles *c*. The turned-over portions are secured to the main portion of the woven strip by the leather or like bands *d*, which may be sewn in place in such a manner that the ends of the said fabric project from the said bands; the projecting ends of the fabric also have the warp threads removed so as to leave a series of projecting hairs *e* constituting a brush at either end of the appliance.

The loops *c* may be fitted, as shown, with hooks or the like *f*, one of which may be suspended after the manner of a razor-strop, and the other be furnished with a tab *g* by means of which the device can be held in one hand when in use.

As will be understood from the description, when it is required to clean a toilet-comb the teeth thereof are passed into the parallel horse-hairs *a* and are drawn from one end of the same to the other, the terminal brushes *e* serving to remove any matter which is drawn out from the spaces be-

tween the teeth of the comb or the like by its passage along the parallel bristles. A special advantage attaches to the employment of horse-hairs derived from the removal of warp threads from a woven horse-hair fabric owing to the fact that in the manufacture of the latter the said hairs have had imparted to them a crinkled, undulating, or wavy form which materially assists in effectively clearing out the spaces between the adjacent prongs of the article to be cleaned.

Figs. 4, 5 and 6 show a form of the appliance which is very similar to that illustrated in Figs. 1, 2 and 3, the main difference being that four layers of the parallel weft horse-hairs are employed. The appliance is built up from a strip of woven horse-hair fabric *b*, which, at the lower end, is passed through the loop *c*, the two lengths of the strip lying face to face being then passed through the upper loop *c* and turned-down, the turned-down portion constituting a brush *e* as in the previously described arrangement. This form of the appliance is utilized similarly to that shown in Figs. 1 to 3.

l are strips of a polishing material such as wool or chamois leather which are secured between the layers of hairs *a*, and serve, as above described, for polishing the prongs of the fork as it is passed between the clearing or cleaning hairs *a*. In this form of the appliance the polishing powder or substance may be employed in conjunction with the leather or like strips for facilitating the action of polishing.

Claims:

1. An appliance for cleaning toothed articles, comprising a strip of woven fabric which is secured at its ends to holding devices, and the warp threads of which between the said holding devices have been removed to form a series of parallel strands, one end of the fabric being folded back through its holding device so as to lie against the main portion of the strip, and the warp threads being removed therefrom so as to provide a parallel series of strands

constituting a brush, substantially as described.

2. An appliance for cleaning toothed articles, comprising a strip of woven horse-hair fabric which is secured at its ends to holding devices, and the warp threads of which between the said holding devices have been removed to form a series of parallel hairs, both ends of the fabric being folded back through the holding devices, so as to lie against the main portion of the strip, and the warp threads being removed therefrom so as to provide a parallel series of hairs constituting brushes, substantially as described.

3. An appliance for cleaning toothed articles, comprising a strip of woven fabric which is folded longitudinally on itself and has its warp threads partially removed so as to provide parallel strands, one end of the fabric being folded back upon itself so as to lie against the main portion of the strip, and the warp threads being removed from said end to provide a parallel series of strands constituting a brush.

4. An appliance for cleaning toothed articles comprising a strip formed of a series of parallel strands which is secured at its ends to holding devices, one of the ends of said strip being folded back through its holding device so as to lie against the main portion of the strip and form a brush, and flexible strips of polishing material carried by said holding devices and lying adjacent to said parallel strands.

5. An appliance for cleaning toothed articles comprising holding devices, a strip formed of a series of parallel strands carried by said holding device, a brush also carried by one of said holding devices and lying against said strip, and flexible strips of polishing material supported by said holding devices and lying adjacent to said strip.

WILLIAM EDWARD LIST.
